APPARATUS FOR TREATING METAL ARTICLES

David C. Turnbull, Mishawaka, Ind., assignor to
American Foundry Equipment Company, Mishawaka, Ind., a corporation of Delaware

Application August 21, 1936, Serial No. 97,099

9 Claims. (Cl. 51—9)

This invention relates to apparatus for treating metal articles.

In cleaning, polishing, hardening, or otherwise treating the surfaces of metal articles by projecting a stream of treating particles thereagainst, it is desirable to manipulate the articles so that the various surfaces of each article are fully and efficiently treated. It is also desirable that the process be carried out continuously, in order to eliminate the necessity for shutting down the apparatus when supplying the articles to the apparatus and removing them therefrom.

According to the present invention, the articles to be treated are deposited on a conveyor having an arcuate, trough-like supporting surface. The conveyor comprises a series of individually movable elements having lugs adapted to engage the articles and cause them to tumble or turn, the lugs also serving to advance the articles along on the conveyor and through a stream of treating material. The articles are fed continuously into the apparatus at one end, passed through the stream while undergoing a forward tumbling action and are thereafter discharged from the apparatus at the other end. One or more abrasive streams of fanlike divergent shape each extending in the direction of the general forward movement of the articles through the apparatus operate to uniformly and thoroughly clean all exposed surfaces of the articles as they are tumbled and progressively advanced through the conveyor. Thus by reason of the cooperative relationship between the fan-like movement of the abrasive particles and the uniform tumbling movement of the articles in the conveyor, highly effective cleaning and treating results are attained.

The apparatus for carrying out the process according to the invention includes one or more abrasive throwing wheels of the rotary centrifugal type, each having means for controlling the direction of flight of the abrasive, operating in synchronism with a conveyor having an arcuate trough-like supporting surface and adapted to carry articles through the stream and turn them about therein. The arcuate article supporting surface is constituted by a plurality of longitudinally extending, generally parallel and relatively closely spaced bars. The bars are mounted for individual rotation and are provided with spaced lugs or abutments which serve to advance the articles upwardly along the side wall of the arcuate surface to a point from which they tumble toward the lower portion of the surface. The abutments preferably have inclined wall portions adapted to 55 advance the articles longitudinally along the sup-

porting surface. The article supporting and tumbling bars may be provided with suitably shaped cam-like blocks fixed thereto or each bar may include a generally cylindrical shaft formed with suitably positioned grooves or flanges. The articles may be deposited on the conveyor from above the conveyor and may be removed by a chute extending from the discharge end. However, if desired, a rotatable feed drum and a discharge drum may be provided for supplying the articles to the conveyor and removing them therefrom or both. The drum is disposed adjacent the end of the conveyor and is formed with spaced, inclined abutments, comprising lugs, flanges or the like, adapted to advance the articles along the drum when the latter is rotated.

The invention provides a method whereby articles to be treated may be positively, effectively and uniformly treated. The articles are tumbled about on the conveyor and each article is carried into the abrasive stream and subjected to thorough uniform treatment. The tumbling action also assists in shaking loose from the articles rust, scale or other adherent foreign matter. The length of the treating period may be positively controlled by proper adjustment of the speed of rotation of the conveyor bars.

The apparatus is relatively simple, yet strong and rugged in construction, and the various parts which receive substantial wear can be quickly and easily removed for repair or replacement. The apparatus is substantially automatic in operation and requires a minimum of attention.

An object of the present invention is the provision of an improved, economical and efficient apparatus for cleaning, polishing, hardening or otherwise treating the surfaces of the articles, whereby the operation may be carried out continuously and substantially automatically.

Another object of the invention is the provision of apparatus for treating metal articles which is simple, rugged, efficient and economical and which uniformly and effectively treats all of the surfaces of the articles.

Another object of the invention is the provision of a combined rotary centrifugal throwing wheel or wheels having means associated therewith for controlling the direction of flight of treating particles to produce a fan-like stream and a conveying mechanism for advancing articles along said stream and for tumbling them about in said stream.

Still another object of my invention is the provision of a novel mechanism for continuously and automatically supplying articles to be treated

to the conveying mechanism for treatment and for removing the articles from said conveying mechanism after treatment.

Various other features and advantages of the 5 invention will be apparent from the following particular description and from an inspection of the accompanying drawings.

Although the novel features which are believed to be characteristic of this invention will 10 be particularly pointed out in the claims appended hereto, the invention itself, as to its objects and advantages, and the manner in which it may be carried out, may be better understood by referring to the following description taken in 15 connection with the accompanying drawings forming a part thereof, in which:

Fig. 1 is a side elevational view of one form of apparatus suitable for carrying out the present invention, certain of the parts being shown 20 broken away and in section in order to expose to view certain interior details of construction;

Fig. 2 is an enlarged transverse cross sectional view of the apparatus taken along line 2—2 of Fig. 1;

Fig. 3 is an enlarged end elevational view of 25 the apparatus shown in Fig. 1;

Fig. 4 is an enlarged perspective view of one of the conveyor roll blocks;

Fig. 5 is a fragmentary side elevational view 30 showing a modified form of apparatus employing rotatable supply and discharge mechanisms, portions of the apparatus being shown broken away to expose the interior;

Fig. 6 is a longitudinal cross-sectional view of 35 the apparatus taken along the line 6—6 of Fig. 5;

Fig. 7 is a fragmentary transverse cross-sectional view showing a modified form of apparatus employing a modified type of conveyor rolls; and

Fig. 8 is a transverse cross-sectional view of 40 the apparatus of Fig. 7, this view being taken along line 8—8 of Fig. 7.

In the following description and in the claims, 45 various details will be identified by specific names for convenience, but they are intended to be as generic in their application as the art will permit. Like reference characters denote like parts in the several figures of the drawings.

In the drawings accompanying and forming part of this specification, certain specific disclosures of the invention is made for purposes of explanation, but it will be understood that the details may be modified in various respects without departure from the broad aspect of the invention.

Referring now particularly to Figs. 1 and 2 of 55 the drawings, there is shown apparatus including a housing 1 having an inlet 2 and outlet 3 and a conveyor 5 extending longitudinally through the housing from the inlet 2 to the outlet 3. Projecting into the inlet 2 is a charging vestibule 6, having an inclined floor 7, the vestibule being closed by one or more flexible curtains 8. Extending from the outlet 3 is a discharging vestibule 10 having a downwardly inclined floor 11, the vestibule being closed by one or more flexible 60 curtains 12.

Suitably mounted in position to project a 65 stream of treating material into the housing 1 is a centrifugal abrasive projector wheel A, hereinafter more fully described. A suitable number of additional projector wheels B and C may be provided, if desired, as for example, where it is desired to provide apparatus of relatively large capacity. Preferably, sufficient projector wheels 70 are provided so that the treating stream or

streams extend over substantially the entire length of the conveyor 5. Where a plurality of projector wheels are employed, certain of them are preferably rotated in opposite directions, whereby to increase the angular range of the 5 components of the abrasive streams.

Each projector wheel generally comprises a plurality of spaced and generally radially arranged throwing blades 16 which extend from adjacent the periphery of the wheel to inwardly short of 10 the center to define a circular opening 22. Disposed in the circular opening 22 is an impeller 23 having a plurality of radially arranged vanes 24 which may be fixed to rotate with the blades 16. Surrounding the impeller 23 is a control 15 member 25 having a discharge opening 26. The control member is mounted independently of the blades 16 and may be adjusted to shift the clock-dial position of the discharge opening 26 whereby the abrasive discharged from the wheel may be 20 directed as desired. Suitable supporting means such as side plates 17 and 18 may be provided for the blades 16. The wheel 15 may be mounted for rotation on a hub 19 carried on a shaft 20 which may be mounted in bearings 21 on the 25 top wall of the housing 1.

The wheel A may be driven from a suitable source of power, such as a motor 31, connected through a suitable drive, such as belt drive 32, to the shaft 20. Upon energization of the motor 30 31, the impeller 23, side plates 17 and 18 and throwing blades 16 are rotated as a unit, the control member 25 remaining stationary. Suitable treating material, hereinafter referred to as "abrasive" is supplied to the wheel through a feed 35 pipe 33 extending through an opening 14 in the side plate 17 and terminating adjacent the impeller 23. The abrasive may be stored in a suitable hopper (not shown) preferably located at a higher level than the wheel so that the abrasive 40 can flow from the wheel by gravity through a suitable pipe such as the pipe 34.

It is to be understood that the term "abrasive" as herein used is intended to include suitable treating material both that which is inherently 45 abrasive and that which exerts a smoothing and polishing action. The abrasive may include smooth steel shot, cracked steel grits, quartz sand or other granular materials suitable for cleaning, polishing, hardening or otherwise modifying the 50 surface characteristics of the articles treated.

When the wheel is rotated as described and abrasive is supplied thereto the abrasive is hurled by impeller 23 through the opening 26 in the control member 25 and into the path of the rotating throwing blades 16. The abrasive is urged along the leading faces of the throwing blades 16 and projected therefrom adjacent the periphery of the wheel 15 by combined centrifugal and radial forces. The abrasive spreads out in a fan-like stream having components extending throughout a considerable range of angularity in the plane of rotation of the wheel 15. The stream forms an elongated, generally rectangular impingement pattern on a horizontal plane disposed below the 60 wheel and extending lengthwise of the conveyor. Other factors remaining constant, the direction of flight of the abrasive may be adjusted by suitable adjustment of the clock dial position of the control member 25. Also, the direction of the 65 stream may be altered by mounting the wheel for rotation in a reverse direction.

A suitable opening 27 is provided in the top 70 wall of the housing 1 to permit the abrasive stream a to be projected into the housing and 75

against the castings or articles supported upon the conveyor 5. If desired, the wheel may be so mounted that a portion of the wheel projects into the housing. A suitable housing 28 may be provided for enclosing the upper portion of the wheel, and one or more baffle plates 30 may depend from the top wall of the housing 1 to protect various adjacent portions of the housing. If desired, certain of the portions of the apparatus 10 which are subject to wear by reason of flying or rebounding abrasive particles may be covered with protective jackets or the like formed of resilient material such as rubber or rubber fabric.

Disposed below the conveyor 5 is a floor which 15 may be shaped to form a hopper 35 adapted to receive and collect abrasive which has been discharged from the wheel. A conveyor, such as the screw conveyor 36, may be disposed in the hopper for conveying the spent abrasive out of the housing 1. A transverse trough 38 in which is disposed a screw conveyor 39 may be provided for conveying the spent abrasive from the hopper 35 to an elevator 41, which may be disposed outside of the housing 1 for returning the spent abrasive 25 to the storage hopper (not shown). The screw conveyors 36 and 39 and the elevator 41 may have sprockets 37, 40 and 42 respectively attached thereto, and suitable driving means may be provided for driving the sprockets whereby to 30 actuate the elevating apparatus.

The conveyor 5 preferably is formed from a plurality of generally parallel and closely spaced rolls 50 extending longitudinally within the housing 1 and arranged to form an arcuate trough-like supporting surface disposed under and in the path of the abrasive streams a, b and c. Preferably, the conveyor is arranged so that the lowermost portion lies directly under the abrasive streams a, b and c and the side walls extend upwardly therefrom on both sides. One side wall of the conveyor may be considerably higher than the other, as will hereinafter appear.

Each roll 50 may comprise a shaft 51 carrying a plurality of blocks 52 arranged on the shafts in staggered arrangement. Referring particularly to Fig. 4, each block may be formed as an oval disc and may have a central boss 54 projecting from each side face. A rectangular opening 55 may extend through the central portion of the block 52 for receiving the rectangular portion 56 of the shaft 51. One face of the block 52 may be formed with tapered faces 57 and 58 adjacent the ends for the purpose of exerting a sidewise pushing action on the articles treated, as herein-after more fully pointed out.

A series of blocks 52 are disposed on the rectangular portion 56 of each shaft with the faces of the bosses 54 of adjacent blocks substantially abutting. The blocks 52 on each shaft are arranged substantially perpendicularly to the shaft on which they are mounted, each block being preferably arranged at approximately a 90° angle to the adjacent blocks. This arrangement of blocks provides a roll having spaced projections formed by the ends of the blocks. The rolls 50 are suitable mounted so that the high portions of each roll, formed by the ends of the blocks, are positioned opposite the low portions of the adjacent rolls thereby permitting the blocks of each roll to clear the blocks of the adjacent rolls when the rolls are rotated.

Each shaft 51 is mounted in a suitable bearing 60 in one end of the housing and a second bearing 61 at the other end of the housing. Either or both of the bearings 61 may be roller bearings.

Bearing 61 is preferably mounted in a bearing housing 62, detachably supported in an opening 59 in the end wall 63 of the housing. Preferably, the opening 59 is of sufficient size to permit the corresponding roll 50 to be removed from the 5 housing 1 for repair or replacement.

Carried on one end of each shaft 51 is a sprocket 64. The sprockets 64 may be driven from a suitable source of power, such as a motor 65, which may drive a speed reducer 66 and a suitable drive 10 67 connected to a shaft 68 mounted in bearings 69 on the top wall of the housing 1. Carried on the forward end of the shaft 68 is a sprocket 70 around which is trained a chain 71, also trained over all of the sprockets 64. Upon energization of 15 the motor 65, the shaft 68 is rotated and all of the sprockets 64 are driven to rotate their respective shafts 51 and thus rotate the rolls 50 in the desired manner.

An end head or wall member 80 may be mounted 20 adjacent the charging end (right-hand end as viewed in Fig. 1) of the conveyor 5 for preventing articles from dropping off the conveyor at this end. The head 80 may include a circular facing member 81 carried by a plate 82 connected as by 25 studs 83 to a plate 84. The head 80 may be fixed in a hollow hub 85 rotatably mounted on a stub shaft 86 by a bearing 87 which may be a roller or ball bearing. The stub shaft 86 is journaled in a bearing 88 mounted on the end wall 63 of the housing. A suitable take-up device 89 may be provided for maintaining the shaft 86, bearing 87, and hub 85 tight relative to the bearing 88. The head 80 is rotatable and hence when the rolls 50 are driven to tumble the articles about there is no tendency for the articles to jam or unduly rub against the head, but the latter rotates as much as necessary to permit free tumbling of the articles.

The operation of apparatus is as follows:

The projector wheels A, B and C are operated in 40 the manner described to project abrasive streams a, b and c against articles supported on the conveyor 5, the stream c being directed reversely relatively to the streams a and b. The articles to be treated are deposited in the charging vestibule 6 45 and slide along the floor 7 and tumble on to the conveyor 5. The motor 65 is energized and drives the rolls 50 to tumble the articles on the trough-like surface provided by the rolls 50. The rolls 50 are driven in synchronism so that the ends of the 50 blocks 52 successively strike against each article and impart an impulse thereto in a direction (to the right as shown in Fig. 2) to cause the article to travel upwardly along the side wall of the conveyor. When the article climbs upwardly along the side wall of the conveyor to a position wherein they exceed their angle of repose, they tumble down over the ascending articles toward the lowermost portion of the conveyor. This action is repeated and each article is carried along a substantially continuous path up along the side of the conveyor and backwardly over the ascending articles a large number of times.

When each block engages one of the articles to drive it upwardly, the inclined face 57 or 58 (as 65 the case may be) imparts an impulse to the article in a direction longitudinally of the conveyor (to the left as viewed in Fig. 1) to advance the article along the conveyor. Thus the articles are both tumbled about and advanced along the conveyor by the action of the rolls.

As the articles advance along the conveyor they are struck by particles of abrasive traveling at high speed which cleans, polishes, hardens or otherwise treats the surfaces of articles in accord- 75

- ance with the nature of the particles used. Since the abrasive streams *a*, *b* and *c* have components extending throughout varying angles, and since the particles are tumbled about in the trough, the articles are struck by abrasive from various angles and thus all portions of the surfaces, including cavities and projections, are fully treated. When the articles reach the discharge end of the conveyors they are forced into the discharge vestibule 10 and slide along the floor 11 and are discharged from the apparatus. If desired, suitable automatic apparatus may be provided for conveying the articles away from the treating apparatus.
- 15 Referring now to Figs. 5 and 6 there is shown apparatus provided with modified charging and discharging mechanisms for supplying the articles to the conveyor and removing them therefrom in an effective manner. The apparatus may 20 be provided with one or more abrasive projector wheels and a conveyor 113 generally similar in construction to those above described. The forward end of the conveyor is open and the adjacent wall of the housing 99 is formed with an opening 25 100 through which projects the charging drum 101. The charging drum 101 is rotatably mounted on a plurality of rolls 105 freely rotatable on pins 106 carried by spaced arms 107 of a supporting frame 108. The rolls 105 may be formed 30 with peripheral grooves 104 adapted to receive circumferential flanges 103 formed on the outside of the drum 101 and spaced sufficiently to support the drum 101 in stable position on the rolls 105.
- 35 The drum 101 may extend into the housing 99 and overlie the forward end of the conveyor 113, whereby articles may be advanced by the drum 101 and deposited on the conveyor 113. The conveyor 113 may be driven from a shaft 109 carrying a 40 sprocket 110 and a chain 111 may be trained over the sprocket 110 and over a circumferential ring sprocket 112 secured to the drum 101. Upon rotation of the shaft 109 the drum 101 is correspondingly rotated.
- 45 The drum 101 may be provided on its inner surface with inwardly projecting, inclined lugs 102 disposed in staggered or echelon arrangement. Upon rotation of the drum, articles which are deposited therein are given a forward movement by the inclined lugs 102 and advanced along the drum 101 and finally are deposited on the conveyor 113.
- If desired, a drum 120, similar to the drum 101 55 may be provided for discharging the articles from the conveyor 113. The drum 120 may be constructed, mounted and driven in a manner similar to the drum 101 except that the lugs 102 thereon are arranged to carry the articles out of the apparatus. The drum 120 preferably is mounted so that the lowermost portion of the floor of the 60 drum is level with the lowermost portion of the floor of the trough provided by the conveyor 113. Thus as the articles reach the end of the conveyor 113 they are deposited in the drum 120 and are carried away from the end of the conveyor 113. The drum 120 may be arranged to discharge 65 the articles into a suitable receptacle or on the floor adjacent to the apparatus or onto a suitable conveyor.
- 70 Referring now to Figs. 7 and 8, there is shown a modified form of apparatus having a conveyor of somewhat modified construction adapted to handle efficiently relatively small articles. The apparatus may be generally similar to that described in Fig. 1 and, if desired, may be provided 75 with a drum 155 constructed, mounted and driven

in a manner generally similar to the drum shown in Fig. 5 and described above:

The conveyor 149 may comprise a plurality of rolls 150 of generally cylindrical form, the ends of the rolls 150 terminating in shaft portions 153 mounted for rotation in suitable bearings 152 suitably supported at the ends of the housing 140. Each roll 150 may be provided with spaced and generally spiral grooves 151 extending partially around the roll. The rolls 150 are mounted so that the grooves 151 of adjacent rolls 150 are offset or in echelon arrangement with the grooves of adjacent rolls.

Each roll 150 may be driven from one or both ends thereof by a sprocket 154 fixed to the shaft portion 153 of each roll. The sprockets 154 are driven synchronously from a suitable shaft 160 mounted in one or more bearings 161. The shaft 160 carries a sprocket 162 and a chain 163 is trained over the sprocket 162 and all of the 20 sprockets 154. Upon rotation of the shaft 160 the sprockets 154 are driven and the rolls 150 driven in synchronism.

The articles to be treated are deposited on the conveyor 149 by the drum 155 or in any other 25 suitable manner. The side walls of the grooves 151 provide moving, inclined abutments which engage the articles and advance them upwardly along the side walls of the conveyor in a manner analogous to that described in connection with 30 the apparatus shown in Fig. 1. The grooves being inclined, also exert a force on the articles longitudinally of the conveyor tending to advance the articles along the conveyor simultaneously with the tumbling action. Abrasive is projected against the articles in a manner similar to that above described and the articles may be 35 discharged from the other end of the conveyor in any suitable manner.

The present invention provides apparatus 40 whereby articles may be effectively and continuously treated by a stream of granular treating material for the purpose of modifying the surface characteristics of the articles in various manners. The articles may be supplied continuously to the apparatus, and the latter need not 45 be shut down except for repair or adjustment. Since the articles are tumbled about in the stream, all of the articles and all portions of the surfaces of each article are fully and completely 50 treated. The articles are positively tumbled and positively advanced and the period of treatment 55 may be closely controlled.

The apparatus provided by the present invention is relatively simple and rugged and is positive in operation. The rolls and other portions of the apparatus which are subject to severe wear from the treating material can be quickly and easily removed for the purpose of repairing or replacing these parts. The apparatus is relatively automatic in operation and can be operated with the minimum of attention on the part of the operator. The apparatus may be employed with suitable automatic apparatus for conveying the articles to be treated to the treating apparatus and removing them therefrom so that the treating apparatus may be installed as a component part of relatively continuous production line.

While certain novel features of the invention 70 have been disclosed and are pointed out in the annexed claims, it will be understood that various omissions, substitutions and changes may be made by those skilled in the art without departing from the spirit of the invention.

What I claim is:

1. Apparatus for treating metal articles including, means for projecting a stream of abrasive material, a concave supporting surface defined by a series of longitudinally extending members, and means for imparting movement to said members for effecting a tumbling movement of the articles treated across said members, and projections on said members for advancing 10 said articles along said surface and through said stream.

2. Apparatus for treating metal articles including, means for projecting a stream of abrasive particles, three or more individually movable 15 supporting elements, means mounting said elements out of line to define a concave supporting pocket for the articles to be treated, and means for rotating said elements individually whereby to tumble said articles in said pocket and advance 20 them through said stream.

3. Apparatus for treating metal articles including, means for projecting a stream of abrasive particles, a series of individually movable elements, means mounting said elements in a 25 series to form a supporting surface for supporting articles to be treated, spaced projections on said elements, and means for rotating said elements whereby said spaced projections impart a tumbling movement to articles and advance them 30 through said stream.

4. Apparatus for treating metal articles including, means for projecting a stream of abrasive particles, a series of individually movable rolls each including a shaft having a plurality of 35 non-circular blocks mounted thereon, means mounting said rolls in proximity to each other whereby said blocks form a supporting surface for the articles to be treated, and means for rotating said rolls individually whereby said 40 blocks engage said articles and impart impulses thereto whereby to tumble said articles about in said stream.

5. Apparatus for treating metal articles including, means for projecting a stream of abrasive particles, a series of individually movable rolls each having a plurality of spaced projections thereon forming abutments, means mounting said rolls in out of line relationship so that the peripheries thereof form a concave supporting 45 pocket for the articles to be treated, and means for rotating said rolls whereby said abutments engage articles to be treated and tumble the same over the rolls and advance the same along said rolls and through said stream.

6. Apparatus for treating metal articles, means for projecting a stream of abrasive particles including, a series of rolls each having a plurality of abutments thereon, means mounting said rolls to form a substantially continuous supporting surface, and means for rotating said rolls whereby said abutments effect a tumbling movement of said articles on said supporting surface and in said stream.

7. Apparatus for treating metal articles including, an abrasive-throwing wheel for projecting a fan-shaped stream of abrasive particles, a conveyor for tumbling articles in and through said stream of abrasive particles, said conveyor having a generally arcuate supporting surface greater than 90° but less than 360° in extent defining therebetween a longitudinal opening through which the abrasive stream is projected against the articles supported upon said arcuate surface, a drum disposed adjacent and extending to said conveyor, a plurality of inclined abutments on said drum, and means for rotating said drum, whereby said abutments engage the articles to be treated and advance them along said drum to said conveyor for treatment, said wheel being so arranged that the particles constituting said fan-shaped stream will strike the article at different angles during the tumbling movement thereof. 5 10 15 20

8. Apparatus for treating metal articles, including, means for projecting a fan-shaped stream of abrasive particles, a conveyor for tumbling articles through said stream of treating material, said projecting means being so arranged that the particles constituting said abrasive stream impinge the article at different angles during the tumbling movement thereof 25 said conveyor having a generally arcuate supporting surface greater than 90° but less than 360° in extent defining therebetween a longitudinal opening through which the abrasive stream is projected against the articles supported upon said arcuate surface, a drum disposed adjacent and extending from said conveyor in position to receive articles from said conveyor, a plurality of inclined abutments on said drum, and means for rotating said drum whereby said projections advance the articles to be treated along said drum and away from said conveyor. 30 35 40

9. Apparatus for abrasively treating metal articles including, a conveyor presenting a trough-like supporting surface, means for imparting a combined lateral shifting, raising and downward tumbling movement and a forward advancing movement of the metal articles on said surface, an abrasive throwing wheel mounted in position to throw a fan shaped stream of treating particles against the articles on said surface, means for rotating said wheel, a second wheel disposed in position to throw a second fan shaped stream of treating particles against said articles, and means for rotating said second wheel oppositely to said first wheel whereby to project a second stream oppositely to said first stream, said wheels being arranged to project their respective abrasive streams against the articles during tumbling and advancing movement thereof with the particles of each stream striking the articles at different angles during 45 50 55 the advancing movement thereof. 60

DAVID C. TURNBULL.
